Patented June 9, 1925.

UNITED STATES PATENT OFFICE.

FRANK A. HOLMGREN, OF MINNEAPOLIS, MINNESOTA.

GAUGE.

Application filed September 24, 1923. Serial No. 664,591.

To all whom it may concern:

Be it known that I, FRANK A. HOLMGREN, a citizen of the United States, residing at Minneapolis, in the county of Hennepin and State of Minnesota, have invented certain new and useful Improvements in Gauges, of which the following is a specification.

This invention relates to builders' tools and the main object is to provide an extremely simple, practical and efficient gauge for marking window frames and sashes upon which are to be secured storm or screen sash hangers. Further and more specific objects will be disclosed in the course of the following specification, reference being had to the accompanying drawing, in which:

Fig. 1 is a perspective view of the gauge.

Fig. 2 is an elevation of the upper right hand corner of a window frame and screen 20 sash, showing a type of hanger whose correct position may be determined by my improved gauge.

Fig. 3 shows the method of applying the gauge when marking a window frame.

Fig. 4 shows the method of applying the gauge when marking a storm or screen sash.

Fig. 5 is a sectional view on the line 5—5 in Fig. 3, showing a modification of the 30 gauge.

Referring to the drawing more particularly and by reference characters, A designates a window frame in which is to be hung a storm or screen sash B. A common 35 type of hanger for this purpose is shown in Fig. 2 and consists of a butt C, secured on the frame A, and a hooking plate D, secured on the sash B, although any type of hanger which is secured by screws or nails may be 40 properly located with the gauge.

Heretofore it has been customary to secure the hanger parts C and D by first fitting the window, putting it in place in the frame, and then by holding the parts C and D 45 together and in their proper places while the screws E are started and screwed home. This method, however, is not only inaccurate but also requires the use of a ladder upon the outside of the building, making the 50 work slow, and, considering the high scale of carpenters' wages, also expensive.

To minimize and reduce the time required for putting on these fixtures and in order to insure an accurate placing thereof, I propose 55 vide a gauge consisting of a sheet metallic plate 6 having perforations 7 and 8, cor-

responding, respectively, to the screw holes of the butt C and the hooking plate D. At the side of the plate 6, and about midway between its ends, is a pair of depending 60 tongues 9 having lateral projections 10, said tongues lying in a common plane and extending at right angles from the plate 6.

The use and operation of the gauge may be briefly described as follows:

When marking the frame A the gauge is placed in the position indicated in Fig. 3, with the tongues 9 against the under edge of the top bar of the frame, and with one of the projections 10 touching the inner side 70 of the adjacent vertical or upright portion of the frame. A scratch awl, pencil or other suitable marking device is then inserted in the holes 7, to mark the screw holes on the frame. The butt C can then be accurately 75 screwed into place without further trouble. The sash B is then properly marked for the screws E of the plate D, as indicated in Fig. 4, the opposite end of the gauge being used. It will be noted however, that the outer 80 edge of the guiding tongue 9 (and not the integral extension 10) is brought flush with the outer edge of the sash, which can easily be done with the aid of the finger, as shown, and, after the sash has been marked through the holes or perforations 8, the plate D can 85 then be secured so that it will properly connect with the butt C when the sash is hung into place. It will be noted that the thickness of the tongues 9 serve to properly space 90 the perforations 7 from the perforations 8 so that a slight clearance will result at the upper end of the sash and the projections 10, similarly serve to clear the sides of the 95 sash from the frame.

In the modification shown in Fig. 5 the perforations 7 and 8 in the plate 6 are substituted by short teats 11, punched down from the plate, which will directly mark the wood, when tapped with a hammer, so that 100 no other scratching or marking device need be used.

It is understood that suitable modifications may be made in the invention as herein set forth, provided, however, that such 105 modifications come within the spirit and scope of the appended claims.

Having now therefore fully shown and described my invention, what I claim to be new and desire to protect by Letters Patent is:

1. A plate having indicating means at

its ends corresponding in relative position to the screws of a window hanger, and transversely arranged guiding devices extending perpendicularly from one face of the plate, and laterally arranged projections extending out from said guiding devices.

2. A gauge of the character described consisting of a perforated plate adapted to be

used in marking the outer surfaces of a window sash and frame, and a pair of ¹⁰ tongues extending perpendicularly from the face of the plate, and having lateral projections at their outer ends.

In testimony whereof I affix my signature.

FRANK A. HOLMGREN.
